(57) **CLAIM**

The ornamental design for a sleeve holder, as shown and described.

DESCRIPTION

FIG. 1 is a top view of a sleeve holder showing my new design, with its clip in a closed configuration;

FIG. 2 is a front view thereof;

FIG. 3 is a right side view thereof;

FIG. 4 is a left side view thereof;

FIG. 5 is a back view thereof;

FIG. 6 is a bottom view thereof;

FIG. 7 is a top view, similar to FIG. 1, but showing the clip in an open configuration;

FIG. 8 is a front view similar to FIG. 2, but showing the clip in an open configuration;

FIG. 9 is a right side view similar to FIG. 3, but showing the clip in an open configuration;

FIG. 10 is a left side view similar to FIG. 4, but showing the clip in an open configuration;

FIG. 11 is a back view similar to FIG. 5, but showing the clip in an open configuration; and,

FIG. 12 is a bottom view similar to FIG. 6, but showing the clip in an open configuration.

1 Claim, 4 Drawing Sheets
